UNITED STATES PATENT OFFICE

2,062,153

KEY PUNCH

Nelson S. Welk and Donald A. Nevin, Athens,
Ohio, assignors to The McBee Company,
Athens, Ohio, a corporation of Ohio

Application September 14, 1935, Serial No. 40,580

7 Claims. (CL 164—112)

Our invention relates to that class of key punches such as are described in the patent to Nelson S. Welk No. 1,981,932.

In the structure therein described it sometimes occurs in practice that the continuous vibration, due to the operation of the parts, will jar the rocker arms 8, into the lowered position, notwithstanding the spring pressed frictional means provided to prevent such an occurrence. Our present invention has for its object to provide an improved construction which will prevent this happening.

A further object is to provide a construction which will eliminate the use of the frictional washers in the device.

It has also been found in practice that during rapid operation of the device that the depression of one of the actuating keys, will carry the adjoining key with it due to the frictional engagement of the friction washers, which separate the keys. This occurs more frequently when two keys which straddle a third key are depressed for the frictional contact will cause the two to carry the third key with them into the depressed position: this is not desired.

A further object is to provide a plurality of guides for the key stem levers, these guides assisting in preventing the movement of adjacent keys.

Our means of accomplishing the foregoing objects may be more readily understood by having reference to the accompanying drawings, which are hereunto annexed and are a part of this machine.

Fig. 1 is a vertical sectional view showing all of the parts in their normal position;

Fig. 2 is a similar view showing a key depressed and the rocker arm in position to punch, the repeat key remaining in its normal position;

Fig. 3 is a vertical sectional view showing a key depressed and the operating lever moved to its lower position, the card (not shown) having been punched, the parts being in their position just prior to their return to normal;

Fig. 4 is a similar view with the operating lever being returned to normal and the punch being retracted from the die;

Fig. 5 is a fragmentary sectional view of the forward key stem lever guide, taken on the line 8—8 in Fig. 2, some parts being omitted for clarity;

Fig. 6 is a fragmental detail view of the rear guide showing the locking springs and plungers, the key stem levers being shown in section, taken

on the line 8—8 of Fig. 2 omitting some of the parts for clearness.

Fig. 7 is a front view of a card which has been punched; and

Fig. 8 is an enlarged detail view of the key locking plungers.

Similar reference numerals refer to similar parts throughout the entire description.

As shown in Figs. 1 and 2 in the drawings the mechanism is enclosed in a suitable casing 1. The casing is provided with a keyboard 2, in which are mounted a plurality of selective keys 3, which may be provided with suitable indicia corresponding to indicia placed on the card adjacent the position to be punched. These cards 15 are fully described in patent to Perkins No. 1,544,172, so a description of them is not deemed necessary here.

Each of the keys 3 is secured in some suitable manner to a key stem lever 5. These levers are mounted to rock upon a shaft 6, which extends from one end wall of the casing 1 to the other end wall. The inner end of each key stem lever 5, is in the same plane as a rocker arm 7, which serves to reciprocate the punches 8. As the rocker arms 7 are duplicates we will describe the construction of a single one only. A slot 9, is provided adjacent the upper end of said rocker arm 7. A rocker arm shaft 10 passes through the slot 9 and all of the rocker arms swing on said shaft when actuating the punches.

A slot 11 is provided in the top portion of the casing 1, in which may be placed the cards which are to be punched.

A suitable die 12 is mounted below the slot 11. In the die 12, are located a number of reciprocating punches 8. Since these punches and their actuation are fully described in the Welk patent referred to we will omit a detail description thereof.

A crank shaft 14, has its ends suitably journaled in bearings (not shown) secured to the end walls of the casing 1. A plurality of crank arms 15 in number corresponding to the rocker arms, are rigidly secured to the crank shaft. Each crank arm 15 is pivotally secured to one end of a connecting link 16, the other end being connected by a pin or pivot to a rocker arm 7, adjacent its lower extremity.

It is apparent from the foregoing description that oscillation of the crank shaft 14 will operate to oscillate on the rocker arm shaft 10. The crank shaft 14 may be oscillated by means of a lever 17, shown in dotted lines, or in any other desired manner.

As shown in Fig. 2, the keys 3, are in elevated or normal position. Pressure upon the operating lever 17 will rotate the crank shaft 14, in counter-clockwise direction and through the medium of the crank arms 15 and connecting links 16, will cause the rocker arm 7 to swing rearwardly without actuating a punch. Upon release of the lever 17 the parts will be restored to normal by means of the tension of spring 13, pulling on the crank arm 15. When a key is depressed as shown in Fig. 2, the inner end of the key stem lever 5 will elevate its corresponding rocker arm 7 to a position in which it can actuate its punch. It is frequently the case that it is necessary to punch a number of cards in the same location. We provide a repeat mechanism such as is described in the copending application of Nelson S. Welk Serial No. 5,182, now Patent No. 2,035,777, but we have not shown the element herein as it is not claimed specifically. Our means to retain the rocker arms in elevated position during the repeat operation is clearly shown in Figs. 2 and 3, and comprises a key stem lever 5, which is formed with an upwardly extending portion 28 25 the edge of which has two V shaped notches 21 and 22, cut or formed therein. A number of spring pressed plungers 23 are provided to engage the notches 21 and 22, one for each key stem lever. These plungers 23, more clearly seen in Fig. 8, are carried by a bar 24 which extends from end to end of the casing 1, and is suitably secured thereto in any convenient manner (not shown). The bar 24 may be conveniently formed as clearly seen in Fig. 8 of the drawings to carry 30 the housing for springs 25 which actuate the plungers 23. Normally as shown in Figs. 1 and 4 the plunger 23 is in notch 21. Depressing key 3 will swing the key stem lever 5 on shaft 6 and this will swing the notches 21 and 22 in an arc 35 and the plunger 23 will move into mesh with notch 22. The springs 25 are of sufficient tension so that regardless of the vibration of the parts the plunger will hold the weight of the rocker arm and its associated parts in their elevated position for the repeat operation. We extend the rearward portion of bar 24 downwardly as at 27 to a position approximately at the center of shaft 6. Slots 28 are cut or formed in this 40 wall for the purpose of guiding the key stem levers 5, and also to separate them, thus aiding in preventing the movement of one or more levers being communicated to another.

This is further facilitated by an additional guide 29 which is mounted below the key board 2, slots 30 forming guides for the front portion 31 of the key stem levers 5. It will be seen from the foregoing that we have provided positive means for overcoming the objections developed 45 in practice, which means will not interfere with the operation of the device.

Having described our invention what we regard as new and desire to secure by Letters Patent is:

1. In a device of the character described, a plurality of rocker arms, a shaft on which they are mounted to permit pivotal and vertical movement of each rocker arm, punches actuated by the swinging of said rocker arms, a plurality of selective keys to designate certain predetermined punches to be actuated by certain of said rocker arms, means actuated by the movement of said keys to elevate said rocker arms, spring pressed means which engage and hold said elevating means in position, positive means to prevent the depression of one key carrying with it an ad-

jacent key, and means to perform a repeat operation.

2. In a device of the character described, a plurality of rocker arms, a shaft on which they are mounted to permit pivotal and vertical movement of each rocker arm, punches actuated by the swinging of said arms, a plurality of selective keys to designate certain predetermined punches to be actuated by certain of said rocker arms, a key stem lever operated by the depressing of a key to elevate a rocker arm into position to actuate its punch, means to perform a repeat operation, positive means to prevent the depression of one key carrying with it an adjacent key, and means which engage said key stem levers to hold certain of said keys in a depressed position.

3. In a device of the character described, a plurality of rocker arms, a shaft on which they are mounted to permit pivotal and vertical movement of each rocker arm, punches actuated by the swinging of said rocker arms, a plurality of selective levers to designate certain predetermined punches to be actuated by certain of said rocker arms, means actuated by the movement of said keys to elevate said rocker arms, spring pressed means which engage and hold said elevating means in position, means to perform a repeat operation, and a bar in which said spring pressed means are mounted, a portion of said bar providing guides for said elevating mechanism.

4. In a device of the character described, a plurality of rocker arms, a shaft on which they are mounted to permit pivotal and vertical movement of each rocker arm, punches actuated by the swinging of said arms, a plurality of selective keys to designate certain predetermined punches to be actuated by certain of said rocker arms, a key stem lever operated by the depressing of a key to elevate a rocker arm into position to actuate its punch, a guide for said key stem levers, means to perform a repeat operation, means which engage said key stem levers to hold certain of said keys in a depressed position, and a second guide located in the forward part of said casing.

5. In a device of the character described, a plurality of rocker arms, a shaft on which they are mounted to permit pivotal and vertical movement of each rocker arm, punches actuated by the swinging of said arms, a plurality of selective keys to designate certain predetermined punches to be actuated by certain of said rocker arms, a key stem lever operated by the depressing of a key to elevate a rocker arm into position to actuate its punch, means to perform a repeat operation, there being notches on said key stem levers, an angle bar which extends across the key stem levers, a housing secured to said bar a plurality of coil springs in said housing one for each key stem lever, plungers actuated by said coil springs which engage said notches to hold the depressed keys in that position.

6. In a device of the character described, a plurality of rocker arms, a shaft on which they are mounted to permit pivotal and vertical movement of each rocker arm, punches actuated by the swinging of said rocker arms, a plurality of selective keys to designate certain predetermined punches to be actuated by certain of said rocker arms, a plurality of key stem levers actuated by said keys, a bar which extends across said key stem levers, and spring pressed means mounted in said bar, a portion of said bar providing guides for said elevating mechanism.

7. In a device of the character described, a plurality of rocker arms, a shaft on which they

are mounted to permit pivotal and vertical movement of each rocker arm, punches actuated by the swinging of said rocker arms, a plurality of selective keys to designate certain predetermined punches to be actuated by certain of said rocker arms, a plurality of spring pressed plungers, a plurality of key stem levers adapted when in a

certain position to be engaged by said plungers, spring pressed plungers mounted in said bar, a portion of said bar providing guides for said elevating mechanism, and a second guide located in the forward part of said casing. 5
